UNITED STATES PATENT OFFICE.

RUDOLPH A. RIEK, OF RHINELANDER, WISCONSIN.

REFRIGERATOR.

Application filed March 27, 1925. Serial No. 18,853.

This invention relates to refrigerators and more especially to refrigerators of that type utilizing enameled one-piece linings better known as porcelain linings.

One of the objects of the invention is to provide a novel form of partition between the ice tank and the side provision compartment of the refrigerator, whereby when the door of the provision compartment is opened, the interior of said compartment will present a massive, costly appearance due to the formation of rounded finishing edges at both sides of the door resulting from the peculiar formation not only of the porcelain lining but also of a portion of the partition.

A further object is to provide a partition for one side of the ice tank and which partition is hollow so that a circulation of air will be set up therein, preventing water of condensation from reaching the contents of the provision compartment and also increasing the efficiency of the refrigerator by more rapidly chilling the air because of the circulation that is set up.

A further object is to provide a partition having a removable plate which can be porcelain covered and which is detachably connected in a novel manner to one side wall of the ice tank, thereby concealing said wall and at the same time giving a massive and finished appearance to that side of the provision compartment nearest the ice tank.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

Figure 1 is a front elevation of a portion of the refrigerator illustrating the appearance of the upper portion of the side provision compartment when the door thereof is open.

Fig. 2 is a horizontal section through a portion of the refrigerator lining and ice tank, said section being taken through the partition.

55

Fig. 3 is a section on line 3—3, Fig. 2.

Fig. 4 is a section on line 4—4, Fig. 2.

Fig. 5 is a perspective view of the removable partition.

Referring to the figures by characters of reference. A designates a portion of the front of the refrigerator and in the present instance a provision compartment B is located within one side portion of the refrigerator while an ice compartment C is located in the upper portion of the other side of the compartment. The lining 1 of the refrigerator is preferably a one-piece seamless lining, the inner surface of which is covered with white enamel. In other words the lining is of the porcelain type. The front of the lining is open and has a continuous flange 2 extending therearound and adapted to be fastened in any suitable manner, as by means of clips 3, to the front frame F of the refrigerator casing. The walls and top of the lining merge into the flanges along curved lines so that when the doors of the provision compartment of the refrigerator are opened, the rounded portions, indicated at 4 will appear adjacent the edges of the door openings and will give the interior of the refrigerator a massive and sanitary appearance resembling that obtained ordinarily only where solid porcelain is used in the very expensive types of refrigerator structures.

The ice chamber is formed by a tank 5 suitably supported within the lining so as to be surrounded thereby. This tank is ordinarily made of galvanized sheet metal and, obviously, this metal does not present an attractive appearance ordinarily when the door of the side provision compartment B is opened. This is due to the fact that all of the walls of the provision compartment have a white enamel finish, whereas that wall nearest the ice chamber is made up solely of galvanized metal and obviously detracts materially from the appearance of the interior of the provision compartment B. Furthermore where the sheet metal side wall

of the ice tank is exposed to view through the side provision compartment, water of condensation collecting on the wall of the ice tank will come into contact with provisions and other contents of the compartment B and often injure them.

It is one of the objects of the present invention to overcome the objectionable features above mentioned by providing that wall 10 of the ice tank which is nearest the side provision compartment, with a partition plate 6, the exposed surface of which is preferably enameled so as to have the same finish as the inner surface of the lining 1. This partition 15 plate has its forward edge rounded as at 7 to correspond with the rounded portion 4 of the lining 1 and from this rounded portion extends a flange 8 in which are provided angular slots 9 extending from the edge of the 20 flange. The lower edge of the partition plate can also be curved laterally so as to produce a rounded finish as indicated generally at 10 and the top of the partition plate is likewise rounded, as at 11, and merges into a top portion 25 12 having a depending flange 13. A rear flange 14 is formed integral with the plate 6 and is likewise formed with angular slots 15. Studs 16 are extended backwardly from the frame F at points near the door opening O 30 in front of the provision compartment B and additional studs 17 can be extended rearwardly from the back wall of the ice tank 5 or can be located at any other suitable point in the back portion of the refrigerator. 35 To place the partition plate 6 in position, it is merely necessary to raise it so that the flange 13 can be slid over the flanged top 18 of the side wall of the ice tank 5. During this movement the open ends of the slots 9 40 and 15 will engage the studs 16 and 17 respectively. When the flange 13 reaches a point past the wall of the ice tank 5, the plate 6 can be lowered. This will cause the inner end portions of the slots 9 and 15 to 45 receive the respective studs and at the same time the flange 13 will drop into the upper portion of the tank 5 so that the partition plate will thus be held properly assembled with the ice tank. 50 With the parts thus located, it will be obvious that when the side provision compartment B is viewed from the front, it will have a symmetrical and massive appearance due to the fact that the forward portions of the 55 side walls thereof are rounded and extend back of the sides of the door opening. This plate also prevents water of condensation from collecting within the provision chamber as the result of ice contacting with the 60 adjacent side wall of the ice tank. Consequently the contents of the provision chamber cannot become damp from water of condensation. Furthermore by providing the 65 plate 6 a supplemental cooling chamber is produced between the side wall of the ice

tank and said plate, this chamber 19 being open at the bottom as shown clearly in Fig. 3. By providing this supplemental chamber, warm air in the lower portion of the refrigerator is free to rise within the chamber 70 where it will be chilled by the wall of the tank 5 and plate 6 and descend within the chamber. Thus air is more rapidly cooled within the refrigerator than would be the case should it be permitted to circulate solely 75 upwardly within the provision compartment and thence downwardly over the ice in the ice-chamber. Plate 6 can be removed readily for the purpose of cleaning it simply by forcing the same upwardly so as to disengage 80 flange 13 from the wall of the ice tank and withdraw the slotted portions of the flanges 8 and 14 from engagement with the studs.

What is claimed is:—

1. In a refrigerator the combination with 85 a front structure having an opening therein for a door, of a porcelainized metal lining mounted back of said structure and having its front edge portions convex and visible at the sides of the door opening, the maximum width of the compartment between opposed 90 sides of the lining being less than the width of the door opening.

2. The combination with the front structure of a refrigerator having an opening 95 therein for the door of a provision compartment, of a porcelain metal lining mounted back of said structure and having its front edge portion convex and visible at one side of said door opening, an ice tank supported 100 within the lining at one side of the provision compartment, a porcelainized partition plate mounted within the lining and concealing one side of the ice tank, said partition plate constituting one side wall of the provision 105 compartment and having a convex front portion exposed at one side of the door opening, the maximum width of said provision compartment between the partition plate and the side of the lining being less than the width 110 of the door opening.

3. In a refrigerator, the combination with 115 a front structure having an opening for the door of a provision compartment, of a porcelain metal lining mounted back of said structure and having a convex side portion exposed through the opening, an ice tank supported within the lining, a porcelainized partition plate supported within the lining 120 for concealing one side of the ice tank, said partition plate having a convex front portion exposed within the door opening at one side, the maximum width of that portion of the provision compartment between the plate and the side of the lining being less than the width 125 of the door opening, said plate and wall of the tank cooperating to form a supplemental air cooling chamber open at the bottom.

4. In a refrigerator, the combination with 130

a front structure and a lining connected to said structure, of an ice tank supported within the lining, a partition plate having front, rear and top flanges, there being slots with-
5 in the front and rear flanges, and means for engagement by the slotted flanges to hold the plate assembled with the ice tank, the top

flange of said plate constituting means for straddling one wall of the ice tank, said plate and tank cooperating to form a supplemental 10 air cooling chamber open at the bottom.

In testimony that I claim the foregoing as my own, I have hereto affixed my signature.

RUDOLPH A. RIEK.
